UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,387,354.

Specification of Letters Patent. Patented Aug. 9, 1921.

Application filed June 5, 1919. Serial No. 301,866.

To all whom it may concern:

Be it known that I, HENRY P. CLAUSEN, a citizen of the United States, residing at Mount Vernon, in the county of Westchester,

5 State of New York, have invented certain new and useful Improvements in Telephone-Exchange Systems, of which the following is a full, clear, concise, and exact description.

This invention relates to improvements in 10 telephone exchange systems and has particular reference to a selectively operable switch therefor.

In systems employing machine switching apparatus controlled by impulses impressed 15 upon a telephone circuit by an impulse sending device, and in which the brushes of a switch are moved directly by said impulses to select a group of trunks and then automatically to hunt an idle trunk in said 20 group, it is possible to manipulate the impulse sending device to transmit another set of impulses intended for a succeeding switch before the automatic trunk hunting operation in the first switch is completed. This 25 results in the mutilation of a call and the probable extension thereof to some other subscriber's line than the one desired, with a consequent annoyance to the subscriber and an unnecessary utilization of switches beyond that in which the trouble occurred.

An object of the present invention is to 30 avoid the above-mentioned difficulties by the provision of novel means whereby, should another set of impulses be transmitted before 35 a switch has completed its trunk hunting operation and seized an idle line, the switch will be returned to normal and maintained in such position until the call is abandoned, and any further impulses will fail to actuate 40 the next succeeding switch.

In accordance with the above object, a circuit is provided for the restoring means of the switch which is closed immediately upon the transmission of the first impulse of 45 a second set to said switch, to operate said restoring means and return the switch to normal, where the same will remain during the transmission of succeeding impulses.

The inventive idea involved is capable of 50 receiving a variety of expressions, one of which, for the purpose of illustrating the invention, is shown in the accompanying drawing; but it is to be expressly understood that said drawing is employed merely for

the purpose of facilitating the description of 55 the invention as a whole, and not to define the limits thereof, reference being had to the appended claims for this purpose.

The drawing illustrates diagrammatically 60 the circuit for a selector switch arranged in accordance with the invention.

It is believed that the invention will be 65 fully understood from the following description of the operation.

Removal of the receiver from its switch-hook at substation A will close a circuit to operate line switch B, which may be of any construction well known in the art, to connect brushes 1, 2 and 3 thereof to terminals 4, 5 and 6 of an idle selector switch C. Line 70 relay 7 of the selector switch will then become energized over a circuit traceable from grounded battery, right winding of relay 7, back contact and inner lower armature of cut-off relay 8, terminal 5, brush 2, apparatus of substation A, brush 1, terminal 4, upper armature and back contact of cut-off relay 8, and left winding of relay 7, to ground. Relay 7 attracts its armature and establishes a circuit for slow-to-release relay 9 extending from grounded battery, 75 winding of relay 9, front contact and armature of relay 7, to ground. Relay 9 energizes, and at its left armature places ground upon conductor 10 which provides a busy 80 test to prevent seizure of selector switch C by any other line switch. This operation takes place immediately upon the seizure of the selector switch, and the subscriber at station A may now manipulate his impulse sending device 11 to transmit a set of impulses 85 to the selector switch corresponding to the first digit of the wanted line.

In response to the impulses transmitted, 90 the armature of line relay 7 is vibrated, and upon each retraction thereof a circuit is closed for primary stepping magnet 12 extending from grounded battery, winding of 95 said magnet, winding of slow-to-release relay 13, front contact and right armature of relay 9, lowermost armature and back contact of cut-off relay 8, back contact and armature of relay 7, to ground. Magnet 12 energizes in response to each retraction of the armature of relay 7, and steps the 100 brushes of switch C in their group selecting movement.

Slow-to-release relay 13 is also energized

in the circuit traced for magnet 12, and in attracting its armature, establishes a circuit for test relay 14 extending from grounded battery, winding of relay 14, armature and 5 front contact of relay 13, to ground. Relays 9 and 13, being slow to release, maintain their armatures attracted during the transmission of the set of impulses, and at the termination thereof the armature of relay 7 remains attracted thus breaking the 10 circuit for primary stepping magnet 12. Relay 13 deenergizes and removes ground from the armature thereof, but test relay 14 remains energized over a locking circuit extending from grounded battery, winding of 15 relay 14, front contact and armature thereof, back contact and right armature of secondary stepping magnet 15, primary off-normal contact 16, which was closed upon the first 20 step of the brushes of switch C, conductor 10, front contact and left armature of relay 9 to ground.

Release of relay 13 establishes a circuit for secondary stepping magnet 15 extending 25 from grounded battery, winding of said magnet, front contact and left armature thereof, back contact and armature of relay 13, front contact and armature of relay 14, back contact and armature of magnet 15, 30 primary off-normal contact 16, conductor 10, front contact and left armature of relay 9 to ground. Magnet 15 energizes and operates to step the brushes of switch C onto the first set of terminals in the selected 35 group.

Should the switch (not shown) associated with this set of terminals be busy, such condition will be denoted by a ground upon the test terminal 18 thereof, and the locking circuit for test relay 14 will then extend from grounded battery, front contact and armature thereof, brush 17, and test terminal 18 to ground. Magnet 15, being self-interrupting, will therefore continue to be operated 40 each time the brush 17 of switch C engages the test terminal of a busy switch, and will step the brushes of switch C until an idle set of terminals in the selected group is found. At such time, magnet 15 and test relay 14, 45 no longer finding ground upon a test terminal leading to the next succeeding switch, will both deenergize and the brushes of selector switch C will rest upon the terminals of said succeeding switch. Release of relay 50 14 establishes a circuit for cut-off relay 8 extending from grounded battery, winding of relay 8, back contact and armature of relay 14, back contact and right armature of magnet 15, off-normal contact 16, conductor 55 10, front contact and left armature of relay 9, to ground. Relay 8 energizes, and in attracting its upper and inner lower armatures extends the telephone line to the next succeeding switch, the line and first slow-to-release relays of which become energized

in the usual well-known manner to provide a holding circuit for relay 8 extending from grounded battery, winding of relay 8, back contact and armature of relay 14, brush 17, terminal 18 and front contact and armature of the slow-to-release relay of said next succeeding switch to ground. This latter ground also provides a busy test for the switches now seized, and extends from terminal 18, brush 17, back contact and right armature of magnet 15, off-normal contact 16, terminal 6 to brush 3, it being understood that relays 7 and 9 deenergized upon the operation of cut-off relay 8, thus removing ground from the left armature of said relay 9.

The subscriber at substation A may now continue to operate the impulse sending device 11 to transmit sets of impulses corresponding to the remaining digits of the called number, to operate succeeding switches until the connection has been established to the wanted line.

At the termination of the conversation the replacing of the receiver upon its switch-hook at the calling and called substations removes ground from test terminal 18 and causes cut-off relay 8 to deenergize. A circuit is then established for release magnet 19 extending from grounded battery, winding of said magnet, secondary off-normal contact 20, which was closed upon the first step of the brushes of the switch C in the trunk-hunting operation, lowermost armature and back contact of relay 8, back contact and armature of relay 7, to ground. Release 100 magnet 19 energizes and operates to return selector switch C to normal position.

Assuming now that after the subscriber at substation A had operated his impulse sending device 11 to transmit the necessary impulses to operate selector switch C, and that before the trunk-hunting operation was completed, he had again operated his sending device to transmit the set of impulses necessary to operate the next succeeding switch. Upon the retraction of the armature of line relay 7, in response to the first impulse of the second set, a circuit would immediately be established for release magnet 19, extending from grounded battery, winding of said magnet, secondary off-normal contact 20, lowermost armature and back contact of cut-off relay 8, back contact and armature of relay 7 to ground. Magnet 19 energizes in this circuit and establishes a locking circuit for itself which extends from grounded battery, winding of magnet 19, resistance 21, front contact and armature of magnet 19, front contact and left armature of relay 9, to ground. Magnet 19 operates 115 to return switch C to normal. As long as the receiver at substation A is off its switch-hook, relays 7 and 9 remain energized, and therefore maintain the locking circuit for release magnet 19 until the subscriber at sub- 120 125 130

station A abandons the call. It will therefore be apparent that any succeeding impulses transmitted by the operation of the sending device 11 will fail to operate switch 5 C, and said impulses cannot therefore be transmitted to any succeeding switches.

What is claimed is:

1. In a telephone system, a switch for extending a call and having directive and automatic movements, means for controlling the directive movements of said switch, other means for automatically moving said switch, and means effective until the call is abandoned for preventing directive and automatic movements of said switch should the first named means be operated before said other means has completed its operation. 15
  2. In a telephone exchange system, an incoming line, outgoing lines, a variably operable impulse sending device for transmitting sets of impulses over said incoming line to extend a call, a switch having brushes responsive to one set of impulses for extending said incoming line to any one of said 20 outgoing lines, and means responsive to another set of impulses transmitted to said switch before the same has seized an outgoing line for restoring the brushes of the switch to normal and maintaining the same 25 in such position until the call is abandoned. 30
  3. In a telephone system, a switch for extending a call and having primary and secondary movements, means for transmitting impulses to said switch to control its primary 35 movements, means for controlling the secondary movements of said switch, and restoring means for said switch operable, when the first named means is actuated before the second named means has completed its operation, to maintain said switch in its restored condition until the call is abandoned. 40
  4. In a telephone exchange system, an incoming line, outgoing lines, a variably operable impulse sending device for transmitting sets of impulses over said incoming line to extend a call, a switch having brushes responsive to one set of impulses for extending said incoming line to any one of said outgoing lines, and a release magnet responsive 45 to another set of impulses transmitted to said switch before the same has seized an outgoing line for restoring the brushes of the switch to normal and for maintaining the same in such position until the call is 50 abandoned. 55
  5. In a telephone exchange system, an incoming line, outgoing lines, a variably operable impulse sending device for transmitting sets of impulses over said incoming line to extend a call, a switch having brushes re- 60
- sponsive to one set of impulses for extending said incoming line to any one of said outgoing lines, a line relay for said switch, a release magnet responsive to another set of impulses transmitted to said switch before the same has seized an outgoing line for restoring the brushes of the switch to normal and for maintaining the same in such position until the call is abandoned, and a circuit for said release magnet controlled by an armature of said line relay. 65
6. In a telephone exchange system, an incoming line, outgoing lines, a variably operable impulse sending device for transmitting sets of impulses over said incoming line to extend a call, a switch having brushes responsive to one set of impulses for extending said incoming line to any one of said outgoing lines, a line relay for said switch, a cut-off relay for extending said incoming line to one of said outgoing lines, a release magnet responsive to another set of impulses transmitted to said switch before the same has seized an outgoing line for restoring the brushes of the switch to normal and for maintaining the same in such position until the call is abandoned, and a circuit for said release magnet controlled through armatures of said line and cut-off relays. 70
7. In a telephone exchange system, an incoming line, groups of outgoing lines, a variably operable impulse sending device for transmitting sets of impulses over said incoming line, a switch having brushes responsive to one set of impulses for extending said incoming line to any one of said outgoing lines, means for controlling said switch to select a group of outgoing lines, means for controlling said switch to hunt an idle line in said group, and restoring means for the 80 brushes of said switch responsive to another series of impulses transmitted to said switch before the same has seized an outgoing line, said restoring means maintaining said brushes in their restored position during the 85 transmission of further impulses. 90
8. In a telephone exchange system, a switch, brushes for said switch, means for transmitting a set of impulses to said switch for directively operating said brushes, means for automatically operating said brushes, and means responsive to another set of impulses transmitted to said switch before the last-named means has completed its operation for placing said switch in a condition 100 from which it cannot be directively or automatically operated. 105

In witness whereof, I hereunto subscribe my name this 28th day of May, A. D. 1919.

HENRY P. CLAUSEN.
